UNITED STATES PATENT OFFICE

RAYMOND K. SINER, OF PHILADELPHIA, PENNSYLVANIA

STOCKING

Application filed December 17, 1931. Serial No. 581,562.

This invention relates to hosiery and of a continuation in part of my co-pending application filed July 13, 1931, Ser. No. 550,455, and has for its primary object the production of a stocking with a unique type of welt which incorporates many novel features including certain that are in great demand in the hosiery industry and which certain manufacturers have attempted to include individually in certain designs of stockings now on the market.

An object of the invention is the incorporation in a single welt unit all desirable features of the trade including the feature of increased elasticity, the feature of a non-run fabric, the feature of an ornamental top and the feature of a welt of single thickness.

Besides the above my invention is distinguished in a design of welt that may be more economically manufactured and more economically applied to a stocking leg thereby materially reducing the cost of manufacture of hosiery.

In the hosiery industry today there is a great demand for a welt of single thickness, a welt of increased elasticity and a welt that may be readily ornamental and which will dispense with the necessity of turning the welt in the manufacture of full fashioned hosiery. I have accomplished these desired objectives by forming the welt of a particular type of fabric and connecting the same to the stocking leg in a unique manner as hereinafter set forth.

With these and other objects in view the invention will be better understood from the following detailed description taken in connection with the accompanying drawings, wherein:

Figure 1 is a side elevation of my improved type of stocking.

Figure 2 is a plan view of the welt strip.

Figure 3 is a plan view of the strip of warp fabric from which the strips are cut.

Figure 4 is a sectional view on the line 4—4, Figure 1.

Figure 5 is an enlarged diagrammatic view of a portion of the welt fabric under normal tension.

Figure 6 is an enlarged diagrammatic view

of a portion of the warp fabric under stretched tension.

Figure 7 is a diagrammatic view illustrating the numerical relation of the welt loops and the leg fabric loops and further their interconnection. 55

Referring to the drawings in detail, the numeral 1 designates my improved welt shown attached, in this particular instance, to a full fashioned knit leg 2 which in turn has attached thereto a full fashioned foot 3.

My improved type of welt is constructed from a special type of material, that is to say, from a warp knitted type of fabric in which the knitted loops extend in a particular direction in relation to the loops of the leg fabric, these loops collectively joining knitted threads of a particular shape and arranged in a particular relation in the welt fabric to give increased elasticity thereto. 65 70

This is an important feature of my invention and is the feature that materially differentiates my invention from various types of hosiery welts heretofore produced.

In the manufacture of the welt I knit on a warp knitting machine a continuous relatively long strip 4 as illustrated in Figure 3, this strip being cut into individual welt strips 5. Due to the particular type of warp knitting machines utilized and the particular construction of the strip 4, each individual welt strip 5 is provided with a plurality of knitted threads 6 of zigzag formation and extending longitudinally of the strip 5 and connected together at spaced points 7 to give increased elasticity to the strip 5 in a longitudinal direction thereof. In the formation of the threads 6, the knitted loops 8 are formed to extend longitudinally of the strip 5 so as to give increased elasticity to the strip in a longitudinal direction and further accomplish a zigzag formation of the threads as clearly shown in Figures 5 and 6. In the knitting of the strip 1 provide along each longitudinal edge 9 thereof an exposed row of loops 10 which are interconnected with the end row of loops 11 forming the leg fabric 12 of the stocking leg 2. This exposed position of the loops 10 of the fabric facilitates the "topping" on operation in relation 80 85 90

95 100

Figure 5 is an enlarged diagrammatic view of a portion of the welt fabric under normal tension.

Figure 6 is an enlarged diagrammatic view

to a flat full fashioned knitting machine in a manner well known in the trade. It is, of course, to be understood that the end row of loops 11 may be connected to the row of loops 10 of the welt fabric by a looping operation well known in the trade and further the welt fabric may be sewed to the leg fabric but I prefer the "topping" on operation as it produces a neater connection at less expense.

10 In producing a stocking in accordance with my invention, the welt strip 5 is cut from the strip of fabric and its exposed row of loops 11 are topped onto the needles of a knitting machine. When this has been accomplished,

15 the knitting machine is set into operation for continuing the knitting of a full fashioned leg fabric having its loops extending in the customary manner, that is to say, longitudinally of the stocking and at right angles to the

20 loops of my improved welt 1. After the leg portion of the stocking has been completed and the foot portion 3 completed by transferring to a "footer" the ends of the welt strip and the edges of the leg fabric are 25 seamed in the customary manner.

Due to the warp construction of the welt, rupture of one of the threads will not start a "run" in the fabric and due to the exact formation of the threads of the welt and the 30 direction of extension of loops thereof, the elasticity of the welt in a longitudinal relation to the length of the hose is considerably increased. Further, the construction of the welt is such that the same may be readily or-

35 namented by changing the relative size and location of the diamond shaped openings defined by the threads. Due to the single thickness of the welt and the nature of the fabric, I produce a stocking without a turned welt 40 and which positively will not curl at the free edge thereof.

I am aware that Patent #1,434,941 illustrates the use of a cuff made from a material known as "tricot" and "milanese" but it is 45 characteristic of this material that the loops extend angularly of the fabric which destroys one of the main objects of my invention, that is to say, the extending of the loops lengthwise of the fabric to increase the elasticity 50 thereof and facilitate "topping" on operations and further arrangement of a longitudinally extending exposed row of attached loops at one edge of the welt strip.

I am also aware of Patent #1,227,217 55 which shows the attachment of a warp fabric to a knitted fabric and therefore I am not attempting to cover broadly the attachment of a warp fabric to a knit fabric but I am claiming the use of a knitted warp fabric of 60 a particular construction attached in a particular manner to a plain knitted fabric.

I am also aware of Reissue Patent #16,053 65 wherein is shown and described a welt unit produced on a circular knitting machine and attached to a full fashioned leg fabric and

therefore I am not attempting to cover in this particular application the broad idea of "topping" on a welt to a leg fabric but I am attempting to cover a method of producing a stocking which consists in topping on a warp 70 knitted welt directly to a plain knitted stocking leg fabric. In concluding, I wish to stress the fact that I am of the opinion that I am the first to knit as a warp fabric a relatively long strip of material, cutting this material 75 into individual welt strips having distinctive structural features and "topping" these individual welt strips on a needle bar to continue the knitting of a stocking leg. I am also of the opinion that I am the first to construct a stocking welt in a manner to have the loops thereof extend around the welt in circular series at right angle relation to the direction of travel of the loops in the stocking leg. 80

I am further of the opinion that I am the first to produce a warp knitted fabric strip with exposed loops along the longitudinal edge thereof for facilitating "topping" on operations or looping operations, the number of loops in the fabric having a definite relation with the number of loops in the stocking leg fabric. 85

I am also of the opinion that I am the first to use a warp knitted fabric welt of the special design illustrated to have considerable increased elasticity in a direction of the required expansion of the welt in the use thereof, that is to say, in a direction at right angles to the leg of the stocking. 90

Therefore, I do not desire to be limited in protection in any manner whatsoever, except as set forth in the following claims.

What I claim is:

1. A method of manufacturing fashioned hosiery which comprises forming the welt of the stocking as a single thickness flat warp knit strip, topping selvage loops of the strip to the needles of a full fashioned knitting machine and continuing thereon the knitting of the leg of the stocking as a full fashioned flat knit web. 105

2. A method of manufacturing fashioned hosiery which comprises warp knitting a web strip to form the welt of the stocking and continuing from the edge portion of the strip a fashioned flat knit web the loops of which extend at right angles to the loops of the welt strip. 115

3. A method of manufacturing hosiery which consists in knitting a strip of warp fabric with finished longitudinal selvage edges, cutting the strip into individual welt strips, topping one of said selvage edges of each individual welt strip onto a needle group of a full fashioned knitting machine and knitting thereto a full fashioned leg web. 120

4. A method of manufacturing hosiery which consists in knitting a relatively long strip of warp fabric of single thickness hav- 125

ing finished longitudinally extending selvage edges, cutting the strip into individual welt strips and attaching to one selvage edge of each welt strip a leg fabric consisting of 5 weft stitches.

5. A method of producing hosiery which consists in producing as a relatively long continuous strip a warp fabric having its loops extending longitudinally of the strip, cutting 10 the strip into individual welt strips, topping to each welt strip a leg fabric of weft stitches, the weft stitches extending at right angles to the loops of the well strip and seaming the 15 ends of the welt strip together and the edges of the leg fabric together.

6. A method of manufacturing hosiery which consists in providing a warp fabric strip having exposed loops along a longitudinal edge thereof and topping onto said 20 exposed loops a leg knitted fabric.

7. In combination with a stocking leg of knit fabric having loops extending longitudinally of the leg, a welt topped thereto and formed from warp fabric having a relatively 25 large series of loops extending around the welt at right angles to the loops of the leg fabric and coacting to produce a plurality of knitted threads of zigzag formation connected at spaced points to give increased elasticity to the welt.

8. In combination with a stocking leg knit fabric having its loops extending longitudinally of the stocking and a welt of warp knit fabric having its loops extending around the 35 welt at right angles to the loops of the leg fabric, said welt further having an exposed series of loops along a longitudinal edge thereof of a number equal to and interlocking with the loops of the leg fabric.

40 9. A stocking having a warp knitted welt having a finished selvage edge provided with exposed loops to provide a topping line readily manipulated for placing on knitting needles and a leg knitted onto said exposed loops.

10. A stocking welt warp knitted and of single thickness having both selvage edges finished with at least one provided with a row of topping on loops.

50 In testimony whereof I have signed this specification this 10th day of December, 1931.

RAYMOND K. SINER.
